UNITED STATES PATENT OFFICE

WALTER W. VAUGHN, OF STOCKTON, CALIFORNIA, ASSIGNOR OF ONE-HALF TO ASA CLARK, OF SAME PLACE.

REFLECTOR FOR SPIRIT-LEVELS.

SPECIFICATION forming part of Letters Patent No. 236,282, dated January 4, 1881.

Application filed September 30, 1880. (Model.)

To all whom it may concern:

Be it known that I, WALTER W. VAUGHN, of Stockton, county of San Joaquin, State of California, have invented a Reflecting Attachment for Spirit-Levels; and I hereby declare the following to be a full, clear, and exact description thereof.

My invention relates to certain improvements in spirit-levels; and it consists in the combination, with a level having the tubes of the level and plumb placed midway between the sides and opening equally to both sides, of a reflector which is pivoted or journaled above the tube, so that the angle of the reflection may be changed from one side to the other, and thrown outward to any desired degree.

It further consists in partially enveloping or coating the bubble-tube with a metallic reflecting-surface, whereby the image of the bubble in the reflector will be rendered more distinct, as will be more fully described by reference to the accompanying drawings, in which—

Figure 1 is a view of the level in a horizontal position, looking at it from below. Fig. 2 shows the plumb in a vertical position. Fig. 3 shows the shape of the reflector by which the image of the bubble is thrown outward so as to be easily seen. Fig. 4 is a modification of the device. Figs. 5 and 6 are side elevation and section of the bubble tube and casing removed, a portion of the casing being cut away, so as to show the metal reflecting-backing of the tube.

A is the body of my level, which is made of wood or metal in the usual manner, and it is provided with a longitudinal central tube, B, filled with a liquid, so as to show a bubble of air in the center when the body A is perfectly horizontal. A transverse tube is fitted in the level, at C, for a plumb, these tubes being similar to the ordinary construction of spirit-levels.

I have shown at E the manner of pivoting or suspending the reflector, so that the image of the air-bubble may be thrown downward and outward to either side and at any desired angle. The journals of this reflector may be

extended from its sides into the sides of the opening in which it is placed, or, if desired, 50 an arm, F, may extend upward from its back and have its upper end pivoted in the top of the opening, as shown in Fig. 4. A spiral spring surrounds the axle of the reflector, and its tension serves to hold the reflector at any 55 angle desired. By this construction the whole mirror may be swung out from the interior of the opening, which will enable it to show the image of the bubble more distinctly.

In order to render the image of the bubble 60 distinct in obscure light or in ordinary use, I have enveloped the bubble-tube with a bright reflecting-surface, H, which extends around beneath it and up the sides, as shown. This envelope may be independent of the tube, or 65 it may be applied directly in the same manner as the back of a mirror.

In order to apply the level to parts which are out of reach, I employ a rod, G, which has a screw cut upon one end. This screw is 70 adapted to fit a socket in one end of the level when it is desired to test the plumb of a vertical post or wall at a considerable height. A similar socket is fitted to the lower side of the level, and the rod may be screwed into this 75 socket to raise the level up to an elevated floor or beam. When not in use the rod may be inserted into a hole (shown in dotted lines, Fig. 1) which is made through the level longitudinally, and by screwing the end into a 80 socket or nut at the farther end of the hole, or by other suitable means, it will be held securely in place.

The additional expense is trifling and the advantages considerable. 85

Having thus described my invention, what I claim as new, and desire to secure by Letters Patent, is—

1. The level A, with its tube C, in combination with the mirror E, situated above the 90 tube and made adjustable, as shown, so as to throw the reflection of an air-bubble downward and outward to any desired angle, substantially as herein described.

2. The level A, with its tubes B C and the 95 mirrors D E, adapted to throw the reflection

of the air-bubble downward, as shown, in combination with the rod G, whereby the level may be applied and observed at points above the observer, substantially as herein described.

3. In a spirit-level, the bubble-tube provided with a metallic reflecting-surface, H, substantially as set forth.

In witness whereof I have hereunto set my hand.

WALTER W. VAUGHN.
